CLAIM

The ornamental design for a medical tool, as shown and described.

DESCRIPTION

FIG. 1 is a perspective view of a medical tool showing our new design;

FIG. 2 is a cut away perspective view thereof taken from line 2-2 in FIG. 4.

FIG. 3 is a bottom plan view thereof;

FIG. 4 is a top plan view thereof; and,

FIG. 5 is a side elevational view thereof.

The broken lines depict portions of the medical tool that form no part of the claimed design.

1 Claim, 5 Drawing Sheets
